UNITED STATES PATENT OFFICE.

GUSTAVE FAST, OF BALTIMORE, MARYLAND.

GEARING.

1,071,719.

Specification of Letters Patent.

Patented Sept. 2, 1913.

Application filed June 13, 1912. Serial No. 703,375.

To all whom it may concern:

Be it known that I, GUSTAVE FAST, of the city of Baltimore and State of Maryland, have invented certain Improvements in 5 Gearing, of which the following is a specification.

This invention relates to certain improvements in what is known as frictional gearing, in contradistinction to gearing in which 10 rotary motion is transmitted from one shaft to another through the agency of toothed wheels; and the object of the present invention, in common with others of its class, is to transmit rotation from one shaft to another at a reduced speed; but it will be seen that the apparatus is also applicable for the attainment of a contrary result.

The said invention, briefly stated, consists principally, in the incorporation in a frictional gearing apparatus in which rotation of the driving shaft is transmitted to the driven shaft by means of rollers and an encircling ring, of an appliance whereby the rollers and the ring, are held together under 25 considerable pressure, as will hereinafter fully appear. To effect this result, I employ as an element of the apparatus, an accurately bored, and exteriorly turned normally resilient and practically closed coiled 30 annulus, together with means whereby its diameter can be changed, and its resilience temporarily suspended, in a manner hereinafter described.

In an apparatus, in which the driven 35 shaft is rotated by rollers having a cycloidal movement derived from a central driving shaft, and inclosed by a fixed annulus with which they are in frictional contact, I form the said annulus of a coiled bar after the 40 manner above briefly described, and surround the same by a closely fitting wedge-shaped appliance which being driven longitudinally of the annulus in one direction, will reduce its diameter and thereby force 45 the annulus tightly in contact with the rollers, and hold the said elements together with "constrictive force".

In an alternative apparatus wherein the frictional rollers perform no revolution 50 around the central driving shaft, but only rotate on their axes, and the ring instead of being fixed as in the former case, is rotated, carrying with it the driven shaft, I secure the coiled resilient annulus upon the central 55 roller, and interpose between the said roller and the annulus, a wedge-shaped appliance

which upon being driven longitudinally of the shaft, diametrically expands the annulus and produces the constrictive force as in the first case.

In the further description of the said invention which follows, reference is made to the accompanying drawings, forming a part hereof, and in which:

Figure 1 is a central longitudinal section 65 of the apparatus constructed as first briefly described, and in which the cycloidal movement of rollers is availed of in connection with the fixed annulus to produce the desired result; and Fig. 2 is a section of the 70 same taken on the broken line $r-r$. Fig. 3 is an enlarged section taken on the broken line $w-w$ in Fig. 1. Fig. 4 is a section taken on the broken line $x-x$ in Fig. 2. Fig. 5 is a central longitudinal section of the 75 apparatus which illustrates the alternate construction in which the rollers have axial rotation only, derived from the driving shaft, and in their rotation produce the rotation of the surrounding annulus which is 80 practically a part of the driven shaft, and in a direction contrary to that of the driver; and Fig. 6 is a section taken on the broken line $y-y$ in Fig. 5.

Referring now to Figs. 1, 2, 3 and 4 of 85 the drawings, 1 is the cylindrical casing of the apparatus, having the lugs 2 whereby it is secured to the foundation represented by the line 3.

4 and 5 are removable heads of the casing 90 1, having suitable ball bearings a and b for the driving and driven shafts denoted by 7 and 9 respectively.

10 is the central or driving roller, keyed to the driving shaft 7, and 12 a cage the hub 95 of which is keyed to the driven shaft 9.

13, 13 are rotary-spindles in ball bearings d which are carried by, and have radial movement in the cage 12; and 14, 14 driven rollers which can be plain solid bodies like 100 the driving roller 10, but by preference are formed of coiled bars forming annuli which inclose the spindles 13, and are supported at their ends only by the collars e of the spindles. The driven rollers are held tightly 105 endwise by the larger collars f one of which is adjustable longitudinally of its spindle and adapted to be forced inward by a suitable nut. The object of constructing the driven rollers 14 in coil form, will be herein- 110 after explained.

15 is the fixed annulus before referred to

as formed of a coiled bar. It is bored to snugly fit the inclosed driven rollers 14, and its outer surface is turned.

17 is a sleeve cylindrically bored to receive the annulus 15, and taperingly turned exteriorly, to present a conical surface *h* which is in contact with a similar surface in the casing 1. This sleeve which is cut longitudinally as shown at *g* in Figs. 1 and 2, to 10 admit of its reduction in diameter, forms a circular non-rotative wedge in one piece as shown, or in sections as hereinafter described, and is forced inward to effect the desired constrictive force which the annulus 15 is to place on the driven rollers; and in order to prevent longitudinal or endwise movement of the annulus in forcing in the wedge, the casing 1 is provided with a stop *i* shown only in Fig. 1.

20 The advantage in constructing the rollers 14 of spiral form as described, over solid ones, consists in that the portion of the rollers in contact with the annulus is slightly yielding, and in consequence, a limited compensation for wear of the abrading surfaces 25 automatically takes place, and independently of the circular wedge 17.

As it is desirable that adjustment of the 30 circular wedge 17 should be effected without removing the head 4, or otherwise interfering with the operating parts of the apparatus, I interiorly thread the portion of the casing which adjoins the head 4, and place therein an externally threaded and internally toothed ring 20 the inner end of which 35 abuts the larger end of the conical wedge; and to the inner end of a shaft 21 which is journaled in the head, is fastened the pinion 23 which is in mesh with the teeth of the 40 sleeve.

On the outer end of the shaft 21 is keyed a worm wheel 24; and on a transversely extending and properly supported shaft 25 having a suitable hand wheel, is fastened the 45 worm 27 by means of which the worm wheel 24, and the pinion 23 can jointly be turned, to drive inward the ring 20 and by means of it, the circular wedge 17, and thereby close the annulus 15 upon the rollers 14 and produce the necessary constrictive pressure on 50 the system of rollers.

From the foregoing description it will be understood that the cycloidal motion of the rollers 14 produces a rotation of the driven 55 in the same direction as that of the driving shaft; and that with the said rollers and the annulus having the relative proportions shown in the drawings, the speed of the driven will be one third of that of the driving shaft.

Referring now to Figs. 5 and 6 of the drawings which represent the alternate construction of the apparatus, before referred to, it will be seen that instead of the fixed 60 coiled annulus 15, and the annular wedge

17 whereby it may be contracted in diameter and made to close upon and produce a desired constrictive pressure on the driven rollers 14 which have a cycloidal motion and impart rotation to the driven shaft 9; I employ an annulus designated by 15^a which forms, practically, the driving roller and communicates rotation to the driven rollers 13^a which in their rotation on their axes in a fixed or immovable cage 12^a, produce rotation of the ring 30 which is secured to and forms practically a part of the driven shaft 9^a.

70 To admit of the diametrical distention of the coiled annulus forming practically a part of the driving roller 15^a there is interposed between it and the said roller, a wedge ring formed of the wedges 17^a which can be forced inward, and held after adjustment, by means of the nuts 31 and the washer 32. 85

By a careful reading of the foregoing, it will appear that although the annuli 15 and 15^a differ in that the annulus 15 is non-rotatable and adapted for closure by means of a wedge exteriorly applied thereto, and the 90 annulus 15^a is rotatable and adapted for distention by means of a sectional wedge applied to its interior, the function of the two devices is the same; viz: that of furnishing means whereby a proper force is attainable 95 to transmit rotation from the driving to the driven shaft, with as little loss of power as is practicable, or in other words, to obtain the maximum efficiency of the apparatus.

I claim as my invention:—

1. In combination with a driving, and a driven shaft, connecting motion-transmitting mechanism which comprises a system of friction rollers and an adjustable pressure-producing element which consists of a 100 resilient coiled annulus, and means whereby the said annulus can be changed in diameter, to force together the frictional surfaces of the mechanism, substantially as specified.

2. In combination with a driving, and a 110 driven shaft in axial alignment, connecting motion-transmitting mechanism which includes a roller fastened to the driving shaft, a system of driven friction rollers, and an adjustable pressure-producing element which 115 consists of a resilient coiled annulus, and means whereby the said annulus can be altered in diameter, to force together the frictional surfaces of the mechanism, substantially as specified.

3. In combination with a driving, and a driven shaft, connecting frictional gearing which comprises as elements thereof, a roller secured to the driving shaft, surrounding rollers in frictional contact with the 125 said roller and adapted to produce rotation of the driven shaft, a resilient coiled annulus, and means whereby the said annulus can be altered in diameter to change the radial distance of the friction rollers with 130

respect to the central roller, and thereby apply a constrictive force upon the rollers, substantially as specified.

4. In combination with a driving, and a driven shaft, connecting friction-roller gearing which comprises as elements thereof, a central driving roller secured to the driving shaft, radially disposed frictional rollers which surround and are in contact with the central roller, a resilient coiled annulus, and means whereby the said annulus can be altered in diameter to apply constrictive force to the central and the radially disposed rollers, substantially as specified.

5. In combination with a driving, and a driven shaft, a roller fastened on the former, and a cage on the latter, rollers carried by the cage which surround and are in frictional contact with the central roller on the driving shaft, a non-rotatable resilient coiled annulus which embraces the system of rollers, and means whereby the said annulus can be diametrically reduced to apply constrictive force to the system of rollers, substantially as specified.

6. In combination with a driving, and a driven shaft, a roller fastened on the former, and a cage on the latter, rollers carried by the cage which surround and are in frictional contact with the central roller on the driving shaft, a resilient coiled annulus which embraces the rollers carried by the cage, a cylindrically bored annular and contractible wedge which surrounds the said annulus, and means for forcing inward the annular wedge to reduce the diameter of the annulus and thereby apply constrictive force to the system of rollers, substantially as specified.

7. In combination with a driving, and a driven shaft in axial alinement, a roller secured on the former, a rigidly attached cage on the latter, a system of rotary spindles having collars thereon, which spindles are carried by the cage, rollers upon the spindles which are formed of resilient coils supported at their ends only by the said collars, a resilient coiled annulus which surrounds the coiled rollers, and means to contract the diameter of the said annulus and so force the coiled rollers against the central roller on the driving shaft, substantially as specified.

8. In combination with a driving, and a driven shaft, in axial alinement, a roller se-

cured on the former, and a rigidly attached cage on the latter, a system of rotary spindles which surround the central roller and are journaled in the cage, rollers upon the spindles, which are formed of resilient coils and are supported by the spindles at their ends only, a resilient coiled annulus which surrounds the coiled rollers, an annular contractible wedge to reduce the diameter of the said annulus and thereby bind the coiled rollers against the central roller on the driving shaft, and means to force inward the said wedge, substantially as specified.

9. In combination with a driving, and a driven shaft, in axial alinement, a roller secured on the former, and a cage which is secured on the latter, a system of rotary spindles having collars thereon, carried by the cage, rollers upon the spindles which are formed of resilient coils supported at their ends only by the said collars, a resilient coiled annulus which surrounds the coiled rollers, and hand operated means to contract the diameter of the said annulus and thereby force the coiled rollers against the central roller on the driving shaft, substantially as specified.

10. In combination with the cylindrical casing of a frictional driving apparatus, a driving, and a driven shaft in axial alinement, a roller secured to the former, and a cage which is carried by the latter, a system of rotary spindles disposed around the driving roller and journaled in the cage, and rollers upon the spindles which are formed of resilient coils supported at their ends only by the spindles, combined with a resilient coiled annulus which surrounds the coiled rollers, an annular contractible wedge to reduce the diameter of the said annulus and thereby force the coiled rollers against the central roller on the driving shaft, a threaded sleeve within the casing, which bears against the larger end of the annular wedge, and a system of spur gearing, together with hand operated mechanism situated exteriorly of the casing, whereby the said wedge can be forced inward to contract the diameter of the said annulus, substantially as specified.
